(57) **CLAIM**

The ornamental design for a fragrance bottle, substantially
as shown and described.

DESCRIPTION

FIG. 1 is a top, front, left side perspective view of our new
design for a fragrance bottle;

FIG. 2 is a left side elevational view of the fragrance bottle
shown in FIG. 1, the right elevational view being a mirror
image thereof;

FIG. 3 is a front elevational view of the fragrance bottle
shown in FIG. 1;

FIG. 4 is a rear elevational view of the fragrance bottle
shown in FIG. 1;

FIG. 5 is a top plan view of the fragrance bottle shown in
FIG. 1; and,

FIG. 6 is a bottom plan view of the fragrance bottle shown
in FIG. 1.
